UNITED STATES PATENT OFFICE.

GEORGE E. STEVENS, OF LYNN, MASSACHUSETTS, ASSIGNOR TO GENERAL ELECTRIC COMPANY, A CORPORATION OF NEW YORK.

DRIVE FOR MACHINE-TOOLS.

No. 800,334.

Specification of Letters Patent.

Patented Sept. 26, 1905.

Application filed March 10, 1904. Serial No. 197,476.

To all whom it may concern:

Be it known that I, GEORGE E. STEVENS, a citizen of the United States, residing at Lynn, county of Essex, State of Massachusetts, have 5 invented certain new and useful Improvements in Drives for Machine-Tools, of which the following is a specification.

The present invention relates to machine-tools, and more particularly to the means for 10 driving such tools.

The object of my invention is to provide a handy arrangement of motor-drive for machine-tools which may be readily actuated into and out of operative relation therewith and 15 the speed at which the machine-tool is driven varied at the will of the operator without the use of current controlling and regulating means.

In the accompanying drawings, which form 20 a part of this specification, I have shown one embodiment of my invention as applied to a sensitive drill-press.

Figure 1 is a broken side elevation with the several parts in operative relation. Fig. 2 25 is a top plan. Fig. 3 is a broken front elevation of the friction-disks and their supports, drawn to a larger scale; and Fig. 4 is a front sectional elevation of the motor and its support, taken on line 4-4 of Fig. 1.

A is the main column of the drill-press, provided with parallel guideways upon which a vertically-adjustable bearing B for the drill-shaft C is secured and has mounted thereon a platen D and a fixed bracket E in which the 35 upper part of the drill-shaft C is journaled. The upper end of the column is extended rearwardly, forming a bracket F, which is provided with lugs 1, carrying a hinge-shaft 2, upon which a motor 3 is pivoted. The drill-shaft C is longitudinally slotted for sliding 40 engagement with a friction drive-disk 4, which rotates in a stationary circular shell 5, supported by the fixed bracket E. The drive-disk 4 is supported in its plane of rotation by 45 a thrust-roller 6, which is journaled in a lug 7 on the upper side of the fixed arm E. The motor 3 has its lugs 8, by which it is pivotally mounted on the hinge-shaft 2, located at its rear end and in the plane of its base, so that 50 its center of gravity falls between the hinge-shaft 2 and the drill-shaft C. The shaft 9 of the motor is extended forward and journaled at its end in an overhanging bracket 10, and a friction-disk 11 to coöperate with the drive-

disk 4 is feathered thereto, so as to transmit 55 the motion of the shaft 9 to the drive-disk 4 in whatever position the roll may be placed thereon.

The means for changing the position of the friction-disk 11 relatively to the axis of rotation of the drill-shaft C, to thereby vary the speed of rotation of the latter, consists of a yoke-piece 12, surrounding the hub of the disk at its inner end and longitudinally movable at its outer end on a guide-rod 13, projecting from the motor-frame parallel to the shaft 9 and to the middle of which a latch-lever 14 is pivoted. The latch-lever 14 is provided at its free end with a handle 15 and at one side near its pivoted end with a latch 65 projection 16, which is adapted to take into a series of notches 17 in the guide-rod 13. The free end of the latch-lever 14 is carried in a guide-box 18, fixed to the forward end of the guide-rod 13, and is normally pressed 70 toward the rod 13 with its latch in engagement with a notch 17 by means of a roller 19, located in the guide-box 18 and having the opposite ends of its shaft 20 engaged by helical springs 21, so that when the position 75 of the disk 11 is to be changed the free end of the latch-lever 14 is moved against the tension of the springs 21 until the latch projection 16 is removed from its notch, and then by a push or a pull upon the lever 14, according 80 as it is desired to decrease or increase the speed of the drill, the friction-disk 11 is moved to a position farther from or nearer to the axis of rotation of the drill-shaft and locked in its adjusted position by the engagement of the latch projection 16 with a corresponding notch 17.

By pivoting the motor in a plane beyond its center of gravity its weight is rendered available to press the friction drive members 95 11 and 4 into working engagement, and in order to vary the pressure exerted by the weight of the motor upon the drive members a leaf-spring 22, adapted to exert a counter-balancing pressure upon the motor, is arranged between the under side of the motor and the top of the column A and connected to the latter by a screw 23. The means for disconnecting the driving member 11 from the driven member to thereby arrest the 100 drill-shaft C without stopping the motor consists of a lever 24, pivoted to one side of the bracket F in such position that its short 105

arm may engage a shoulder or surface of the motor and tilt the latter upward when the lever is actuated from the full-line position to the dotted position in Fig. 1.

5 I do not desire to restrict myself to the particular form or construction of parts herein described and shown, since it is apparent that they may be changed and modified without departing from my invention.

10 What I claim as new, and desire to secure by Letters Patent of the United States, is—

15 1. The combination in a machine-tool, of a vertical shaft, a friction-disk connected thereto, a pivotally-supported motor having its shaft arranged at an angle to the first shaft and provided with a friction-disk adapted to rest upon the side of the first friction-disk, and means for tilting said motor to engage and disengage said friction-disks.

20 2. The combination in a machine-tool, of a vertical shaft, a friction-disk connected thereto, a motor pivotally supported at its rear end and having its shaft arranged at an angle to said vertical shaft, a friction-disk connected

25 to said motor-shaft and adapted to engage the side of the first friction-disk, and a lever pivoted upon a stationary part and adapted to engage said motor to tilt it and disengage said friction-disks.

3. In a machine-tool, the combination of a 30 drive-shaft, a driven shaft, coöperating friction-disks connected to said shafts, and means for adjusting the position of one of said disks relatively to the other comprising a yoke-piece, a notched guide-rod and a spring- 35 pressed latch connected to said yoke-piece and engaging the notches of said guide-rod.

4. In a machine-tool, the combination of a drive-shaft, a driven shaft, coöperating friction-disks connected to said shafts, and means 40 for adjusting the position of one of said disks relatively to the other comprising a yoke-piece in engagement at one end with the friction-disk, a notched guide-rod in engagement with the other end of said yoke-piece and 45 arranged parallel to the axis of said disk, a guide-block secured to said guide-rod, a latch-lever pivotally connected to said yoke-piece and adapted to engage said notches and a spring carried by said guide-block and operating to force said lever into locked position.

In witness whereof I have hereunto set my hand this 8th day of March, 1904.

GEORGE E. STEVENS.
